BLADE STROPPING DEVICE

Willard Reid, New York, N. Y., assignor to Magazine Repeating Razor Company, New York, N. Y., a corporation of New Jersey

Application March 25, 1941, Serial No. 385,041

5 Claims. (Cl. 30—40)

The invention relates to implements that may serve as holders for stropping safety razor blades and for injecting blades into safety razors of the magazine type and ejecting worn blades therefrom.

The object is a device of that character that will hold the blade firmly in place during stropping and which may also be used to inject the stropped blade into a razor head directly from its position in the holder, at the same time causing the ejection of a blade (if any) already in the head.

Referring to the drawing:

Fig. 1 is a top plan view of the implement;

Fig. 2 is a view in side elevation;

Fig. 3 is a view of the left end of Fig. 2;

Fig. 4 is a view similar to Fig. 3 but in another operating position;

Fig. 5 is a view on the line 5—5 of Fig. 1;

Fig. 6 is a view on the line 6—6 of Fig. 1;

Fig. 7 is a view on the line 7—7 of Fig. 1;

Fig. 8 is a perspective view showing the parts in position preparatory to injecting a blade into a razor head;

Fig. 9 shows a modification.

Referring more in detail to the drawing, the operative parts are mounted on or carried by a hollow shank 10 which terminates at one end (right end in Fig. 1) in an enlarged portion 11, the bore 12 of the shank being correspondingly enlarged as shown at 13. Within the bore 12 is rotatably and slidably located a shaft 14 which terminates at one end in a finger 15 projecting at right angles from it, the purpose of which will be presently explained. The other end of the shaft enters a bushing 16 rotatably mounted in the enlarged bore 13 and terminating in a knob 17 whereby the bushing may be rotated by the thumb and finger of the operator. The connection between the shaft 14 and the bushing 16 is effected by the pin 18 entering the helical groove 19 in the shaft. This groove extends about one-quarter way round the shaft, and within the limits of its angular scope the shaft is rotatable in the bushing. The purpose of this construction will likewise be presently explained. Endwise motion of the bushing 16 in the enlarged portion 11 of the shank is prevented by crimping over the rim of the enlarged portion as shown at 16a.

A blade clamp composed of the two clamping jaws 20 and 21 extends laterally from the hollow shank 10, these jaws being, if desired, of spring material and normally capable of exerting a slight resilient pressure on a blade A positioned between them. For use with narrow blades a blade

seat 22 may be inserted in the slot which serves as a backing for the blade. Need for this blade seat or a blade seat of different dimensions depends upon the width of the blade to be used with the implement. However, as will appear, it is best that the edge of the blade be extended a considerable distance from the hollow shaft 10 and in the case of narrow blades—say blades in the neighborhood of .315" in width—such a seat is desirable.

Extending from the lower clamp 21 is an aligning finger 23, the plane of which is normal to the plane of the blade in the slot and therefore the material of the finger is shaped into a bracket 15 to effect this purpose.

When it is desired to strop a blade, the blade is inserted between clamping jaws, and the knob 17 is turned as far as it will go in the direction of the arrow 24a (Fig. 2), which causes the finger 15 to be rotated into position as shown in Fig. 1, whereby it serves as a closure for one of the open ends of the blade clamp slot. Its limit of motion in this direction is reached when it contacts with the upper portion of the bracket 24.

At the same time there is a camming action between the thread 19 and the pin 18 which draws the closure finger 15 closely against the end of the blade, which is thereby firmly held between it and the plunger which will be presently referred to. The implement is then ready for stropping the blade, the clamping jaws holding the blade firmly and the finger preventing the blade from being dragged endwise toward the finger.

Closure of the opposite end of the slot is effected by the plunger 25 which is connected to the sleeve 26 but offset from it, the sleeve 26 being slidably mounted on the hollow shaft 10. Preferably the plunger 25 is long enough so that, when the sleeve is retracted as far as it can go (as shown in Fig. 1), the tip end of the plunger lies between the clamping jaws preventing rotation of the sleeve 26.

The plunger 25 also serves another purpose—viz., that of injecting a blade, such as the blade A, into a razor—such, for example, as is illustrated in United States Patents to Rodrigues, No. 1,965,945, issued August 14, 1934; Hilliard, No. 2,221,379, issued November 12, 1940; and Morris, No. 2,203,837, issued June 11, 1940. The razors of all these patents have the common characteristic of a separate magazine provided with a finger for projecting into the razor head in order to align the blade ejection orifice of the magazine with the blade retaining passage in the

razor. Consequently, the implement may be used not only for holding a blade for stropping but also as a means for injecting blades into razors of the type referred to.

Of course the positional relationship between the finger and the blade clamping slot, and the dimensions would be co-ordinated to suit the particular razor with which the implement is to be used.

For definitely locating the angular position of the finger 15 when it is serving as a closure for the end of the blade clamping slot, it is advisable to provide an internal keyway 27 in the bore of the shank 10 which co-operates with a key 28 on the shaft 14—that is to say, when the shaft 14 has been turned by manipulation of the knob 17 to the position shown in Figs. 1 and 3 where the end of the blade clamping slot is covered, further rotation of the knob 17 draws the key into the keyway, thus positively fixing the angular position of the finger and preventing it from accidentally turning during the stropping operation. For ejecting the blade and inserting it into a razor, the plunger is operated by merely seizing the sleeve 26 and forcing it to the left until the blade in the holder—e. g., the blade A—is located properly in the razor, the blade (if any) already in the razor being ejected therefrom.

In the case of the sleeve 26 of Fig. 1, it is advisable that it fit the shank 10 closely enough to produce a slight friction, i. e., enough to keep it in any desired position lengthwise of the shank. In the form shown in Fig. 8 a clamping ring 30 is threaded as shown in 31 on the sleeve. By screwing up or backing off the clamping ring, the sleeve may be tightened or loosened, which effects a positive means of positioning it anywhere along the shank.

Fig. 9 shows the device adapted simply for stropping; in other words, it is similar to Fig. 1 except that the mechanism for ejecting a blade from the blade clamp is omitted, and likewise the aligning finger.

I have described above certain embodiments of my invention, but I wish it to be understood that this is illustrative and not limitative of my invention and that I reserve the right to make various changes in form, construction, and arrangement of parts falling within the spirit and scope of my invention, as set forth in the claims.

I claim:

1. An implement adapted to serve as a holder for stropping a razor blade and injecting the blade into the shaving head of a razor, comprising a hollow shank, a blade clamp extending laterally from the shank, means for closing one end of the clamp and for ejecting a blade therefrom comprising a plunger slidably mounted on the shank and extending into the clamp, and means for opening and closing the other end of the clamp comprising a shaft rotatably mounted in the shank and carrying a finger laterally extending therefrom in a plane adjacent the last-mentioned end.

2. An implement adapted to serve as a holder for stropping a razor blade and injecting the blade into the shaving head of a razor, comprising a hollow shank, a blade clamp extending laterally from the shank, means for closing one end of the clamp and for ejecting a blade therefrom comprising a plunger slidably mounted on the shank and extending into the clamp, and means for opening and closing the other end of the clamp comprising a shaft carrying a finger laterally extending therefrom, the said shaft being rotatably mounted in the bore of the shank and the said finger extending in a plane adjacent the last-mentioned end.

3. An implement adapted to serve as a holder for stropping a razor blade and injecting the blade into the shaving head of a razor, comprising a hollow shank, a blade clamp extending laterally from the shank, means for closing one end of the clamp and for ejecting a blade therefrom comprising a plunger slidably mounted on the shank and extending into the clamp, and means for opening and closing the other end of the clamp comprising a shaft rotatably and slidably mounted in the shank and carrying a finger laterally extending therefrom in a plane adjacent the last-mentioned end.

4. An implement adapted to serve as a holder for stropping a razor blade and injecting the blade into the shaving head of a razor, comprising a hollow shank, a blade clamp extending laterally from the shank, means for closing one end of the clamp and for ejecting a blade therefrom comprising a plunger slidably mounted on the shank and extending into the clamp, and means for opening and closing the other end of the clamp comprising a shaft rotatably and slidably mounted in the shank and carrying a finger laterally extending therefrom in a plane adjacent the last-mentioned end, and means for rotating the shaft and for effecting a longitudinal motion thereof.

5. An implement adapted to serve as a holder for stropping a razor blade and injecting the blade into the shaving head of a razor, comprising a hollow shank, a blade clamp extending laterally from the shank, means for closing one end of the clamp and for ejecting a blade therefrom comprising a plunger slidably mounted on the shank and extending into the clamp, and means for opening and closing the other end of the clamp comprising a shaft rotatably and slidably mounted in the shank and carrying a finger laterally extending therefrom in a plane adjacent the last-mentioned end, means for rotating the shaft and for effecting a longitudinal motion thereof, the finger being provided with a key adapted to enter a keyway in the hollow shaft when the finger is in closure position, and means for rotating the shaft and causing it to slide in the bore of the shank.

WILLARD REID.
